UNITED STATES PATENT OFFICE.

CLARENCE M. EVELETH, OF RIVER FOREST, ILLINOIS.

SHADE-ADJUSTER.

1,368,128.

Specification of Letters Patent. Patented Feb. 8, 1921.

Application filed April 24, 1919. Serial No. 292,345.

To all whom it may concern:

Be it known that I, CLARENCE M. EVELETH, a citizen of the United States, residing at River Forest, in the county of Cook and 5 State of Illinois, have invented certain new and useful Improvements in Shade-Adjusters; and I do declare the following to be a full, clear, and exact description of the invention, such as will enable others skilled in 10 the art to which it appertains to make and use the same.

This invention relates to shade adjusters, and it relates more specifically to an improved vertically adjustable window-shade 15 supporting and guiding device.

One object of this invention is to generally improve upon devices of this character, and especially to improve, simplify and cheapen the device disclosed in my Patent 20 No. 1,249,936, dated December 11, 1917, these improvements comprising such angular adjustability that enables the device to work easily and quietly under adverse conditions where other devices of this character are unsatisfactory.

Other objects and advantages may become apparent to persons who read the following details of description in connection with the accompanying drawings, in which:

30 Figure 1 is an elevation of the window frame having my improved shade adjuster attached, the same being viewed from the inner side of the window frame.

Fig. 2 is an enlarged horizontal sectional view, the section being taken along the line 35 2-2 of Fig. 1.

Fig. 3 is a vertical sectional detail view, the section being taken along the line 3-3 of Fig. 1.

40 Fig. 4 is a fragmental detail, in elevation, as viewed from the outer side of the window frame, showing the adjustable connection of the guiding bar with the shade-supporting bar.

45 Fig. 5 is a view showing the right-hand side of the shade adjuster in elevation, the window frame being in vertical section along the line 5-5 of Fig. 1.

Fig. 6 is a top plan view of one end of the 50 shade adjuster, the window frame and track being in horizontal section.

Referring to these drawings in detail, in which similar reference characters correspond with similar parts throughout the several views, and in which the window frame 55 7 and the shade 8 may be of any ordinary or

appropriate construction, and the elements 23, 24, 25, 26 and 27 being the same as the similarly designated elements of my prior patent:

This device comprises a shade support or bar 28, a guide 29, a track 30 and other elements which will hereinafter be mentioned and described. The shade support 28 has the usual shade bearings 31 and 32 secured at 65 its opposite ends, and the inner side of the bar 28 is provided with extensions or flanges 33 which extend horizontally past the track's sides which face toward one another, so as to prevent movement of the shade support outwardly with relation to the window frame. 70 These extensions 33 may be in the form of sheet metal plates which are secured to the main portion of the support 28 by means of screws, as indicated in the drawings, and the 75 shade brackets or bearings 31 and 32 may be secured on these plates or extensions by any appropriate means or formed integrally therewith.

Referring now to Figs. 2, 3 and 4, it will 80 be seen that the bar or shade support 28 has an extension 34 which overlaps the outer surface of the track 30. This extension 34 may be formed on a connecting member or plate 35, by screws or other appropriate 85 means, and the end surface of the extension 34 is curved or bulged at its middle portion, as indicated at 36. At opposite sides of the bulge 36 the member 35 is formed with apertured ears 37, and screws 38 extend through these ears into screw-threaded engagement with the guide 29. By referring to Fig. 2, it will be seen that the holes through which the screws 38 extend are sufficiently large to permit angular adjustment 90 of the elements 29 and 35 with relation to one another, and the screws 38 are operable to effect such angular adjustment by first loosening one screw, then tightening the other. This angular adjustment of the 100 elements 29 and 35 is an important feature of this invention, as it permits this device to be quickly, easily, and properly applied to window frames which are out of plumb, that is, to window frames in which 105 the upright sides lean toward or from the center of the window, as is often the case because of inaccuracy in building or because of the uneven settling of a wall in which the window is supported. In this 110 connection, it should be understood that it is desirable and important that the axis of

the shade roller should be practically horizontal, if not the shade will roll toward and extend from one end of the roller so as to cause inconvenience in raising and 5 lowering the shade, also causing the shade to wear out this edge, and sometimes spread the shade-brackets so that the shade-roller becomes disengaged therefrom. In order 10 that my shade support 28 shall be practically horizontal at all times, regardless of the inclination of the window frame sides from the vertical, it is important that the 15 guide 29 be held substantially in a fixed angularity with relation to the window frame, and that the angularity of the shade support be adjusted accordingly; and therefore, the guide 29 is held substantially in 20 parallel relation with the track 30 by means of a flange 39 of this track, said flange extending outwardly of the window frame and being spaced from the window frame's 25 surface to which it is attached. In the space between the flange 39 and opposing surface of the window frame a lower roller 40 and upper rollers 41 are journaled on the guide or bar 29; and in practice, the roller 40 rolls on the contiguous surface of the flange 39 while the rollers 41 roll on the contiguous surface of the window frame 30. This is true because the raising and 35 lowering means 23 is connected to the shade support in such position that the end of the shade support which carries the guide 29 slightly overbalances the other end of the shade support, thereby pressing the rollers 41 against the window frame while 40 pressing the roller 40 against the flange of the track. The purpose of two rollers 41 is to enable this guide to ride over nail-holes, knot holes, and other depressions 45 which often exist in new as well as old window frames. It will be seen that while one of the rollers 41 is opposite to one of such depressions and tends to enter same, the other of said rollers is likely to be riding on a comparatively smooth or plain 50 surface.

As an auxiliary to the flanges or extensions 33, the guide 29 may be provided 55 with an arm or angular retaining member 42 which extends outward from the guide 29, thence toward the middle of the window frame, thence inward of the window frame and thence away from the center of the window frame, thereby passing from the outer to the inner side of the track 30 and coöperating therewith and with the associated flange 33 for holding the rollers 40 and 41 in the space between the flange 39 and window frame.

Although there are two of the tracks 30 and they are of counterpart construction, as disclosed herein, the left-hand track 30 in Fig. 1 may be of a different construction, 60 but it is important that the right-hand track

30 be substantially of the construction illustrated in Fig. 2, that is, it should be substantially L-shaped, being preferably formed integrally of wood and provided with apertures through the larger one of its 70 flanges for receiving nails and for securing it to the window frame. This provides a substantially noiseless track which can be formed at a comparatively slight expense 75 with a wood working machine for such purposes and can be cut in suitable lengths, with an ordinary saw or knife, for fitting windows of different heights.

Although I have described this embodiment of my invention very specifically, it 80 is not intended to limit this invention to these exact details of construction and arrangement of parts, but changes may be made within the scope of the inventive idea, 85 as specified and claimed.

What I claim as my invention is:—

1. In a shade supporting and guiding device, the combination of substantially horizontally extending shade-supporting means, 90 track-engaging means on one end of the shade-supporting means, and means to effect angular adjustment of said track-engaging means with relation to the horizontal extent of said shade supporting means.

2. In a shade supporting and guiding device, a substantially horizontally extending shade-support adapted to be attached to a window having an upright track, a guide adapted to travel along said track and be held thereby substantially in a fixed angularity relative thereto, and means to secure said guide to said shade-support, said means being operable to effect angular adjustment of said guide relative to the horizontal extent of said shade-support.

3. In a shade supporting and guiding device, a shade-support adapted to be attached to a window having an upright track, a guide adapted to travel along said track and be held thereby substantially in a fixed angularity relative thereto, said shade-support comprising a bulged surface and two apertured ears, these ears extending respectively upward and downward from the bulge of said surface, and screws extending through said apertured ears and engaging with said guide and holding the latter against said bulged surface, said screws being operable to effect angular adjustment of said guide relative to said shade-support.

4. In a shade supporting and guiding attachment for a window frame, a track secured in an upright position on the window frame and comprising a flange that extends outwardly of and in parallel and spaced relation to the window frame, a substantially horizontally extending shade-support, a bar secured to one end of the shade-support and extending downward therefrom,

means to adjust said bar angularly with relation to the horizontal extent of said shade-support, rollers on the upper and lower ends of said bar and disposed in the space between said flange and the adjacent part of the window frame, and an angular retaining member on said bar and extending across the side of the said track opposite to said flange and being effective to retain the rollers in said space.

5. In combination, a shade-support, a guiding track vertically disposed at one end of the shade-support and comprising a flange, a guiding bar carried by said end of

the shade support, a roller journaled on the lower end portion of the guiding bar in a position to roll along on said flange, a plurality of rollers journaled on the upper end portion of said guiding bar in a position to roll on the window frame, and means to raise and lower said shade-support, said means being so connected to the shade-support that the end which carries said guiding bar and rollers slightly overbalances the other end of the shade-support.

20 In testimony whereof I have hereunto set my hand.

CLARENCE M. EVELETH.
